WATCH STRAP

Anthony R. Lo Curto, Brooklyn, N. Y.

Application December 8, 1944, Serial No. 567,139

1 Claim. (Cl. 224—4)

The wrist watch cases in general use have, at their sides, two pairs of lugs or outstanding arms which are provided adjacent their outer extremities with aligned openings. The pair of aligned openings at each side of the watch case are adapted to receive a pin. Each pin may be inserted through a stitched loop at the end of the watch strap. In some cases the pins are sprung into the aligned openings, and in other cases the pin is made up telescopically, with a spring holding the two members of the telescopic pin extended when the pin is held by one pair of the watch case arms.

It frequently happens that one of the pins will become dislodged from its aligned openings of the watch case arms, so that the watch is not held upon the wearer's wrist by the normal holding means of buckle or clasp, and the watch drops and is lost.

Many devices have been proposed for preventing the dislodgement of the watch case and strap after a strap pin has pulled away from the watch case arms. As an example a leather piece has been stitched to the two sections of the strap so as to underlie the watch case and rest directly upon the wearer's wrist. While such means is effective, it has been found undesirable.

The specific object of my invention is to provide simple and effective means for insuring the continued connection of a watch strap, with the watch case and watch held thereby, upon the wrist of the wearer, notwithstanding the pulling away of one of the watch case pins.

My device will be described with reference to the accompanying drawing, in which

Fig. 1 is a plan view showing an embodiment of the invention, a watch being held by the strap, the view being taken from the outer face of the watch.

Fig. 2 is a plan view, the strap sections being partly broken away and showing the under-face of the structure.

Fig. 3 is a view similar to Fig. 2, with the watch case removed.

Referring to the drawing I have shown at 1 a watch case having at each side two outwardly extending arms 2. Each pair of arms will have aligned apertures at 3, Fig. 1, to receive a pin 4. At 5, 5x, I have shown two strap sections, one section having a buckle 6 to receive the other strap section which is formed with a row of apertures for coaction with the buckle.

The inner ends of each strap section are looped or otherwise formed to provide sleeves at 6 to receive one of the pins. In the present embodiment each watch strap section, at 7, is provided with a second sleeve to receive my special safety device. The latter consists of a flexible strand 8 passed through both of these sleeves 7, and its ends connected at the rear faces of the strap sections. This strand may be of any strong and yieldable material, such, for example, as braided cord, silver or other metallic wire, or even narrow tape. My safety device may have its lengths at the rear face of the watch case crossed, as in Figs. 2 and 3, but this is not at all essential.

The advantage of my safety device is that it adds no bulk or weight of any consequence to the watch and strap structure, it is yielding and entirely tolerable to the wearer, it involves very little cost, and it affords adequate protection.

For clarity of illustration I have shown my flexible member 8 as a cord tied at its ends, but it will be understood that whatever the form of the flexible member 8 may be, i. e. tape, ribbon, braided or plain wire or cord, the end connection may be in the form of a safety catch, or a socket and internally threaded retaining member at one end to coact with a threaded pin carried by the other end, etc. In short, the ends of the flexible member may be connected by a simple tie, or by mechanical means, as desired.

Having described my invention, what I claim and desire to secure by Letters Patent is as follows:

A watch strap consisting of two elongated sections held in spaced relationship, means at the free ends of the sections for fastening them together, such means permitting unfastening, a pair of loops carried by the inner ends of the strap sections and adapted to receive removable pins carried by the watch case, a second pair of loops carried by each strap section adjacent to the first pair of loops, and a continuous flexible strand threaded reversely through the second pair of loops so as to present a cross formation intermediate said two pairs of loops, said strand having its ends connected and thereby being adapted to securely restrain the strap sections against separation.

ANTHONY R. LO CURTO.
